APPARATUS FOR MANUFACTURING ICE

Filed Jan. 17, 1929

UNITED STATES PATENT OFFICE

FRANK HANUS, OF CLEVELAND, OHIO

APPARATUS FOR MANUFACTURING ICE

Application filed January 17, 1929. Serial No. 333,198.

This invention relates to an apparatus for manufacturing ice and has particular relation to the construction of the freezing tank and the ice molds arranged therein.

5 In large ice manufacturing apparatus, the ice is formed in separate molds which are placed in the freezing tank in spaced rows. The freezing tank is filled with a cooling or heat absorbing medium, such as brine, in 10 which the molds are submerged. In some forms of freezing tanks, cooling pipes or coils submerged in the cooling or heat absorbing medium run longitudinally therethrough between the rows of ice molds and 15 convey heat from the cooling or heat absorbing medium to a point where final removal of the absorbed heat is made, while in other forms of freezing tanks, the coils or pipes are arranged at the end of the tanks in the 20 cooling or heat absorbing medium but serve the same purpose. In both types of freezing tanks, however, the cooling or heat absorbing medium is caused to have a positive flow between the ice molds by the use of propellers, 25 pumps or other means. It is customary to so construct the ice molds that they are substantially narrower at the bottom than at the top for the purpose of facilitating ice removal and to insure the formation of the ice 30 from the bottom to the top. As is well known, the time required for freezing solid the water within the mold depends upon the thickness of the mold and naturally, since the molds are narrower at the bottom than at the top, 35 it will take a considerably longer time to freeze the water at the top of the mold into solid ice than it does to freeze the water in the bottom of the mold. This difference in time is augmented by the fact that the down- 40 wardly tapered shape of the molds permits a much greater volume of cooling medium to pass between the lower part or sides of the molds than can pass between the tops of the molds, thus more rapidly extracting the 45 heat from the water at the bottom of the molds than from the water at the top of the molds. This difference in freezing time between the bottom and top of the molds has proven to be a serious obstacle to the efficient and economical manufacture of ice.

The principal object of the present invention is to provide an apparatus for manufacturing ice wherein a more efficient control of the volume of flow of the cooling or heat absorbing medium in the freezing tank between the sides of the ice molds, will be effected, so that the volume of flow of such medium will be more nearly proportional to the cross-sectional thickness of the ice to be formed in the various ice molds or in the different portions of such molds, thus tending to equalize the time required for freezing the water at the bottom and at the top of the molds.

Additional objects and advantages will 65 become more apparent herein as the detailed description of several embodiments of the invention proceeds.

The present invention contemplates the reduction of the difference in time required 70 for the freezing of the water at the bottom and top of the ice molds in the freezing tank of an ice making machine, and in accomplishing this, it is proposed to so regulate the volume of flow of the cooling or heat 75 absorbing medium between the rows of ice molds that an equal volume of flow of such medium will occur between the sides of the molds at all points, or the volume of flow of such medium between the sides of the 80 molds will increase proportionately to the thickness of the molds at different points.

In the accompanying drawing, illustrating several embodiments of the invention,

Fig. 1 is a fragmentary vertical sectional view through the freezing tank of an ice making apparatus, the ice molds being shown in end elevation;

Fig. 2 is a view corresponding to Fig. 1 but showing a slightly different form of freezing tank;

Figs. 3, 4 and 5 are isometric views of different forms of ice molds;

Fig. 6 is a horizontal sectional view through a plurality of ice molds, such as are shown in Fig. 5, arranged in spaced rows in a freezing tank, the section of the containers being taken approximately on line 6-6 of Fig. 5;

Figs. 7 and 8 are views similar to Fig. 6, the sections for the containers being taken, 100

respectively, on lines 7—7 of Fig. 4 and 8—8 of Fig. 3.

In ice making apparatus, it is customary to provide a relatively large freezing tank, the top of which is usually arranged adjacent the floor level, while the bottom thereof is supported upon the ground, as indicated at 1 in Figs. 1 and 2. These tanks generally comprise a metal container 2, which is suitably heat insulated by insulating material 3, such as cork, arranged along the bottom and sides of the container. The form of construction of the freezing tank may be conventional since it does not of itself constitute a part 10 of the present invention and, therefore, will only be described herein to an extent necessary to show the relationship between it and that part of the ice making apparatus which includes the inventive subject matter.

As previously stated, these tanks are filled 20 with a heat absorbing or cooling medium and have submerged in such medium a plurality of ice molds 4 arranged in spaced rows. This cooling medium is caused to flow between the rows of ice molds by propellers, pumps or 25 other suitable means, while in one form of freezing tank, the cooling pipes or coils 5 also extend between the rows of ice molds and are submerged in the cooling or heat absorbing medium, as illustrated in Fig. 1. In another form, they are arranged in another 30 part of the freezing tank (usually at the back of the tank), Fig. 2 illustrating this latter form.

The molds are supported at their lower 35 ends by the bottom of the tank but have their bottoms suitably arranged a slight distance above the bottom of the tank, such arrangement being accomplished either by 40 extending the sides of the molds below the bottoms thereof or by providing suitable raised supporting cleats upon the bottom of the freezing tank. The upper ends of the 45 molds extend, of course, above the level of the cooling or heat absorbing medium in the tank and are maintained in suitably spaced relationship by spacing means, such as for example, the spaced girders 6, shown in Fig. 1. Separate doors or hatches 7 may be provided for the different molds where it is 50 desired to "harvest" only one or two molds at a time, as shown in Fig. 1, or a single door 8 may be provided for the entire freezing tank where it is desired to "harvest" more than one 55 or two molds at a time, as shown in Fig. 2.

The ice molds 4 are downwardly tapered so that the bottom portion of the molds is considerably narrower than the upper portion thereof, while the width of the spaces between the rows of molds is correspondingly wider adjacent the bottom of the molds than it is adjacent the top of the molds. Consequently, a greater volume of the cooling or heat absorbing medium may flow between the rows 60 of the molds adjacent the bottom portions

thereof than can flow between the same adjacent the top portions thereof. This naturally results in causing the water in the molds to freeze more rapidly at the bottom of the molds than at top, which fact, when it is realized that there normally is a large difference in the time required for freezing the water at the top of the molds than at the bottom thereof, such time being proportional to the thickness of the molds, results in making this time difference so large as to constitute a serious handicap to the efficient and economical manufacture of the ice. It is thus proposed to regulate or control the volume of this flow of cooling or heat absorbing medium between the sides of the rows of ice molds so as to materially reduce this time difference.

This proposal may be accomplished in a variety of ways, several preferred methods of which are disclosed herein. In Fig. 1, the molds are shown as provided with flanges or baffles 9 arranged at their four corners and projecting laterally therefrom into the spaces between the rows of molds. This form of mold also corresponds to the mold illustrated in Figs. 4 and 7. The side walls 10 of the mold taper downwardly as before to facilitate the removal of ice, while the flanges or baffles 9 diminish in width as they approach the top of the mold and thus constitute baffles extending into the spaces between the molds so as to obstruct the flow of the cooling or heat absorbing medium between the side walls of the rows of molds and reduce the volume of such flow. In this form of mold, the flanges 10 are arranged so that their outer edge is in vertical alignment with the side wall of the mold at the top thereof, causing the volume of flow of the cooling medium to be substantially equal throughout the depth of the spaces between the rows of molds.

In the form of freezing tank shown in Fig. 2, where there are no cooling pipes or coils 5 in the spaces between the rows of molds, it is possible to extend the flanges 5 laterally outwardly adjacent the bottom of the molds beyond the vertical projection of the top portion of the side walls thereof so as to increase the obstruction to the flow of the cooling medium adjacent the bottom and thus have the volume of such flow less at the bottom of the molds than at the top. In this way, the volume of flow may be made proportional to the thickness of the molds at various points in their depth.

In Fig. 3, the mold 4 is shown as provided with laterally extending upwardly diminishing baffle flanges or ribs 11 arranged medially of the side walls of the mold, while in Fig. 5, the mold 4 has upwardly extending and diminishing baffle flanges or ribs 12 arranged at corners of the mold on opposite ends and on opposite sides thereof. It should be understood that whichever form of mold is

used, the principle is the same and that the lateral baffle flanges or ribs will extend into the spaces between the molds and will form an obstruction to the flow of the cooling or heat absorbing medium therebetween thus providing that the volume of such flow will be substantially equal at the top and bottom of the molds or will increase proportionately to the increase in the width of the mold, according to the width and construction of the flanges or ribs.

In the preceding description, the mold has been shown as arranged to have the cooling medium flow along the broad sides thereof, this being typical of most standard ice making plants but it should be understood that the molds may be so arranged that the cooling medium will pass along the narrow sides thereof, the baffle ribs or flanges, of course, being correspondingly positioned to perform their function. Although the baffles have been shown as applied to the ice molds, they may be arranged between the rows of molds as, for example, they may be carried by bulkheads arranged in such spaces when no coils or cooling pipes are positioned therein, or when coils or cooling pipes are arranged in the spaces between the rows of molds, as shown in Fig. 1, the baffles could be secured to the pipes of the coils and would perform the same function.

Although several preferred forms of the invention have been illustrated and described and other possible forms thereof have been suggested herein, it should be understood that the invention is susceptible of various modifications and adaptations within the scope of the appended claims.

Having thus described my invention, what I claim is:

1. In an ice making apparatus of the type having a freezing tank within which a plurality of downwardly tapered ice molds in spaced rows are submerged in a cooling or heat absorbing medium adapted to flow between the rows of molds, means for obstructing the flow of such medium in the spaces between the rows of molds in proportion to the downward taper of the molds.

2. In an ice making apparatus of the type having a freezing tank within which a plurality of ice molds in spaced rows are submerged in a cooling or heat absorbing medium adapted to flow between the rows of molds, baffles arranged in the spaces between the rows of molds and upwardly diminishing in width for controlling the volume of flow of such medium between the rows of molds so as to more nearly equalize the time required for freezing water at the top and bottom of the molds.

3. In an ice making apparatus of the type having a freezing tank within which a plurality of ice molds in spaced rows are submerged in a cooling or heat absorbing me-

dium adapted to flow between the rows of molds, baffles carried by the molds and extending into the spaces between the rows and formed to control the volume of flow of such medium between the rows of molds in direct proportion to the volume of water to be frozen in different parts of the molds.

4. In an ice making apparatus of the type having a freezing tank within which a plurality of downwardly tapered ice molds in spaced rows are submerged in a cooling or heat absorbing medium adapted to flow between the rows of molds, baffles carried by the molds and extending into the spaces between the rows and upwardly diminishing in width for controlling the volume of flow of such medium between the rows of molds so as to more nearly equalize the time required for freezing water at the top and bottom of the molds.

5. In an ice making apparatus of the type having a freezing tank within which a plurality of downwardly tapered ice molds in spaced rows are submerged in a cooling or heat absorbing medium adapted to flow between the rows of molds, baffles carried by the molds and extending upwardly from adjacent the bottom thereof and formed to control the volume of flow of such medium between the rows of molds in direct proportion to the volume of water to be frozen in different parts of the molds.

6. In an ice making apparatus of the type having a freezing tank within which a plurality of downwardly tapered ice molds in spaced rows are submerged in a cooling or heat absorbing medium adapted to flow between the rows of molds, baffles carried by the molds and extending upwardly from adjacent the bottom thereof, said baffles upwardly diminishing in width and projecting into the spaces between the rows of molds so as to more nearly equalize the time required for freezing water at the top and bottom of the molds.

7. An ice mold adapted to be used in a freezing tank of an ice apparatus comprising an elongated container of diminishing width toward the bottom, said container having a vertically extending flange projecting laterally from a wall thereof and upwardly diminishing in width.

8. An ice mold adapted to be used in a freezing tank of an ice apparatus comprising an elongated container of diminishing width toward the bottom, said container having vertical flanges extending laterally from opposite walls thereof and upwardly diminishing in width.

9. An ice mold adapted to be used in a freezing tank of an ice apparatus comprising an elongated container of diminishing width toward the bottom, said container having a flange projecting laterally from a wall thereof and extending upwardly with diminishing

width from a point adjacent the bottom of the container toward the top.

10. An ice mold adapted to be used in a freezing tank of an ice apparatus comprising an elongated container of diminishing width toward the bottom, said container having a plurality of flanges projecting laterally from opposite walls thereof and extending upwardly with diminishing width from adjacent the bottom of the container toward the top.

11. In an ice making apparatus of the type having a freezing tank within which a plurality of ice molds in spaced rows are submerged in a cooling or heat absorbing medium adapted to have a positive flow between the rows of molds, means for increasing the volume of flow of such medium from the bottom of the molds toward the top thereof.

20 12. In an ice making apparatus of the type having a freezing tank within which a plurality of ice molds in spaced rows are submerged in a cooling or heat absorbing medium adapted to positively flow between the 25 rows of molds, means for controlling the volume of flow of such medium in direct proportion to the volume of water to be frozen in different parts of the molds.

13. In an ice making apparatus of the type 30 having a freezing tank within which a plurality of ice molds in spaced rows are submerged in a cooling or heat absorbing medium adapted to flow between the rows of molds, baffles arranged in the spaces between 35 the rows of molds and varying in width from end to end for decreasing the volume of flow of such medium between the molds from one end of the molds toward the opposite end thereof.

40 In testimony whereof, I hereunto affix my signature.

FRANK HANUS.
